MEANS FOR FILLING ORDERS IN RETAIL STORES

Lansing P. Shield, Ridgewood, N. J.

Application November 8, 1938, Serial No. 239,504

2 Claims. (Cl. 186—1)

This invention relates to improved means for filling orders in retail stores. As it is applicable particularly to retail grocery stores it will be described hereinafter with reference to such stores for purposes of illustration. It should be understood, however, that the invention may be used in many other types of stores and other establishments for filling orders for merchandise.

One of the objects of this invention is to provide means to effect a concentrated disposition of stocks of merchandise of all classes, such as fast and slow moving commodities, packaged, canned and bottled articles, loose articles, and perishable and non-perishable products, in such manner that the entire stock of the store will be displayed simultaneously and will be within reach of those ordering or selecting diverse articles therefrom.

Another object is to provide means for displaying the entire stock of the store at all times within reach of those ordering or selecting diverse articles from time to time.

Another object is to provide means to effect an assembly of the entire stock of merchandise irrespective of the diverse character of the several classes of merchandise in a concentrated and restricted area in such manner that selectors will be able to examine and select from said stock in a minimum amount of time and with a minimum amount of movement by clerks and customers throughout the store.

Another object of the invention is to provide means whereby the largest variety of products may be so disposed in the smallest amount of space in each store so as to achieve the greatest distribution of items sold.

Another object is to provide means whereby special sales and forced sales of high profit items will be reduced to a minimum.

A further object of the invention is to provide means whereby the working conditions of clerks will be made less arduous.

A further object of the invention is to provide means whereby the operating costs will be minimized while effecting improvements in service to customers.

The foregoing and other objects and features of the invention will appear from the following description thereof, in which reference is made to the accompanying drawings illustrating a typical embodiment of the invention as applied to a retail grocery store.

In the accompanying drawings:

Fig. 1 is a diagrammatic plan view of a typical retail grocery store embodying the invention;

Fig. 2 is a side elevation of a preferred form of storage and display means and means for conveying articles selected by customers or others; and

Fig. 3 is a detailed plan view illustrating an alternative form of a portion of the construction shown in Fig. 1.

In the invention as illustrated in the drawings, a store having a front 2 with a door 4 and display windows 6 is provided with suitable storage 10 and display means or units 8, such as cabinets or shelving, disposed adjacent the side walls and the rear of the store and one or more refrigerating units 10 for perishable commodities such as butter, milk, eggs, cheeses, etc., positioned in alignment with the storage and display means 8. As illustrated in Fig. 2, the units 8 are constructed preferably with a lower section 12 extending outwardly of an upper section 14, thereby providing a horizontal support 16 adjacent the sections 12 and 14 and the unit 22 and the aisle 30, hereinafter described, for tracks or other suitable means 18 on which baskets or other receptacles 20 for conveying merchandise may be mounted and propelled manually. This preferred form of construction also provides greater storage and display space for merchandise in the unit 8. At the same time it enables the receptacles 20 to be propelled along the tracks 18 and the support 16 without interfering with the storage and display of merchandise in the lower section 12 and in the upper section 14. It, furthermore, provides means whereby selectors of merchandise may remove articles from the unit 8 without interference by the support 16 or a receptacle thereon, regardless of whether the articles to be selected are stored and displayed above or below the said support and receptacle.

The unit 10 is constructed preferably in the same manner as the unit 8 to provide a continuation of the support 16 adjacent the unit 10. The compartments of the refrigerating unit 10 are provided with doors, not shown in the drawings, above and below the support 16, said doors being fitted with glass windows so that the articles stored in the unit 10 are displayed visibly to persons selecting merchandise. The doors may be of any suitable type but are preferably of the sliding type so that the opening and closing of the doors will not interfere with the movement 50 of receptacles along the support.

The preferred form of construction of the units 8 and 10 as described above enables selectors to remove articles from the said units and from the unit 22 hereinafter described and to transfer the 55

selected articles without loss of time or motion to receptacles on the adjacent tracks 18.

While the preferred form of construction of the units 8 and 10 and the support 16 is described above, it will be understood that the said units and support may be of any suitable or convenient construction.

The support 16 is positioned between the top and the bottom of the units 8 and 10 at a height adapted for the convenient movement of the receptacles 20 by selectors of merchandise and terminates at one end thereof in a counter 24 behind which clerks are stationed at 26. The receptacles 20 are mounted preferably on rollers or otherwise equipped to facilitate their movement along the tracks 18 on the support 16 when loaded with merchandise. When not in use the receptacles may be stored on racks or in any other suitable manner at 28.

20 As shown in Fig. 1, the store is also provided with a storage and display means or unit 22. This unit may be of the same construction as the preferred form of construction of the units 8 and 10 and may be provided with tracks for the movement of receptacles for the conveyance of selected articles of merchandise to avoid congestion of receptacles on the tracks 18 referred to above or the unit 22 may be of any other desired form of construction. If the preferred form of construction of the units 8 and 10 is employed, the unit 22 may be provided with a counter and stations for clerks similar to the counter 24 and the stations 26 described above.

25 The aligned units 8 and 10 with the support 16 and the tracks 18 thereon are positioned to extend substantially around the interior of the store and adjacent the side walls and the rear thereof. The unit 22 is positioned substantially in the center of the store and adjacent the support 16 and at the same time is positioned with respect to the units 8 and 10, the support 16 and the tracks 18 to provide a continuous aisle 30 extending substantially around the interior of the store from a point adjacent the door 4 to a point adjacent thereto and adjacent the counter 24, as illustrated in Fig. 1. This arrangement enables selectors to propel loaded receptacles along a continuous path without lifting them from one support to another.

30 If desired, the storage and display units 8 and 10 may be dispensed with at any convenient point, as shown in Fig. 3, to provide an entrance 32 to the storeroom 34 at the rear of the store for the convenience of clerks and others. 35 If this construction is employed, the support 16 and the tracks 18 thereon may be extended acrosss the entrance 32 by any suitable means, as, for example, by employing a separate section 33 which may be raised by means of hinges 36 to facilitate entry into and exit from the storeroom when desired. The section 33 is provided with tracks 18 and may be lowered into horizontal position by means of the hinges and movably fixed in such position by any suitable means 40 so that the section 33 and the tracks 18 thereon register respectively with the support 16 and the tracks 18 thereon, thereby permitting continuous movement of the receptacles 20 from the support 16 to the section 33 and across the entrance 32.

45 Aisles 38 may be provided, if desired, for convenience in placing stock in the units 8 and 10 from the rear thereof and also as additional means of entrance to and exit from the storeroom 34.

It will be seen that the invention enables selectors of merchandise to pass from the door 4, to obtain a receptacle 20 from the rack at 28, and, after placing the receptacle on the adjacent tracks 18, to proceed directly along the continuous aisle 30, to withdraw articles from a widely diversified assortment of merchandise comprising fast moving and slow moving articles, packaged, canned and bottled products, perishable and non-perishable commodities, and loose articles positioned on both sides of the continuous aisle 30 and in the units 8, 10 and 22, to transfer the articles withdrawn from said units to the receptacles 20 mounted on the tracks on the support 16 on one side of said continuous aisle, 15 and to propel the receptacles with the articles therein along the support from point to point while withdrawing other articles from the said units and proceeding simultaneously from the door 4 to the counter 24 and back to the door. 20 It will be seen also that this invention makes it possible for each selector to make a complete circuit of the store in the most direct path possible and that in making a single circuit of the store all classes of merchandise stocked are on 25 display and are within reach of each selector. The withdrawal of the several articles of diverse character comprising each order is thereby accomplished without loss of time, with a minimum amount of motion and without wandering 30 from shelf to shelf or from one part of the store to another, as is prevalent in other non-self-service and self-service stores.

When the selectors complete their respective circuits of the store and arrive at the counter 35 24, the articles withdrawn from the units 8, 10 and 22 may be removed from the receptacles 20 by clerks stationed at 26 and placed in containers for removal from the store after payment has been made. The receptacles may be accumulated 40 and stored temporarily beneath the counter 24 and may be removed at any convenient time to the racks at 28.

In practicing the invention, it is preferred to position all fast moving products in the units 45 8 and 22 in the cartons or cases in which they are received at the store after first removing portions of the cartons or cases to permit withdrawal of the articles remaining therein. It is preferred, on the other hand, to remove all slow 50 moving products from the cartons or cases in which they are received at the store and to position such articles in the individual packages, cans and bottles in the units 8 and 22. This method saves time which is of the most importance in the case of the fast moving products and saves space in the case of the slow moving products, replenishment of the latter stock being least often required and the saving of time being, therefore, of less importance. 55

It will be obvious from the foregoing description that the invention effects improvements in the storage and display of the diverse classes of merchandise comprising the stock of a retail grocery store and eliminates the inefficient method and means in use heretofore with the delays suffered by selectors of merchandise, the constant moving about of customers and clerks, the loss of time and labor, and the high rate of operating expense. It will be obvious also that this invention accomplishes the storage and display of a widely diversified assortment of merchandise of all classes, such as fast moving and slow moving products, packaged, canned and bottled articles, perishable and non-perishable commodi- 70 75

ties, and loose articles in a small and restricted area and permits the withdrawal from the concentrated assembly of a maximum number of articles in a minimum amount of time, with a minimum amount of moving about by selectors of merchandise, whether clerks or customers, with a minimum amount of work and expense, and in a wide distribution of articles of the several classes in the total sales of the store.

10 It should be understood that the invention is capable of changes and modifications to lend itself to any particular set of conditions and that the foregoing description is merely illustrative of the invention.

15 I claim:

1. A self service store including in combination a doorway, continuous shelving arranged substantially in the form of a U, the ends of said shelving being contiguous to said doorway, said shelving being spaced inwardly from the walls of the store for providing a space for clerks between the shelving and the walls of the store, said shelving being open at both sides and accessible for replenishment by clerks back of said shelving at the same time customers are removing articles from the front of said shelving, said shelving further comprising wide lower sections and superposed narrower upper sections, the

projecting tops of the wider lower sections defining a continuous, U-shaped shelf for the slid-
able passage of receptacles therealong, both sets of shelving holding groceries within easy reach of a customer walking along in front of said 5 U-shaped shelf.

2. A self service store including in combina-
tion a doorway, continuous shelving arranged substan-
tially in the form of a U, the ends of said
shelving being contiguous to said doorway, coun-
ter means between the ends of the shelving and
the doorway for the reception of filled and un-
filled receptacles, said shelving being spaced in-
wardly from the walls of the store for providing
a space for clerks between the shelving and the 10 walls of the store, said shelving being open at
both sides and accessible for replenishment by
clerks back of said shelving at the same time
customers are removing articles from the front
of said shelving, said shelving further compris-
ing wide lower sections and superposed narrower
upper sections, the projecting tops of the wider
lower sections defining a continuous, U-shaped
shelf for the slidable passage of receptacles there-
along, both sets of shelving holding groceries 15 20 25 within easy reach of a customer walking along in front of said U-shaped shelf.
